KNITTING MACHINE

Robert H. Lawson, Pawtucket, and Roy F. Lovell, Providence, R. I., assignors to Hemphill Company, Central Falls, R. I., a corporation of Massachusetts

Application March 2, 1934, Serial No. 713,726

13 Claims. (Cl. 66—125)

This invention relates to knitting machines and especially to knitting machines of the type disclosed in the Hemphill Patent 933,443, September 7, 1909 and wherein the needle cylinder reciprocates to effect the knitting of so-called split-foot work.

In the drawings:

Fig. 1 is a view in side elevation showing the path taken by the thread on its way to the needles of the knitting machine;

Fig. 2 is a view in rear elevation of the mechanism shown in Fig. 1;

Fig. 3 is a view in front elevation, relatively enlarged, showing a portion only of the mechanisms shown in Figs. 1 and 2;

Fig. 4 is a fragmentary view similar to Fig. 1 but showing the latch ring in an elevated, inoperative position;

Fig. 5 is a detail fragmentary view showing one of the supporting brackets shown in Fig. 1 depending from which is an indicator or yarn measuring device;

Fig. 6 is a detailed fragmentary view partly in section showing the indicator or yarn measuring device;

Fig. 7 is a view in plan showing a bracket which carries a thread marking device;

Fig. 8 is a view in rear elevation of the thread marking device shown in Fig. 7; and

Fig. 9 is a fragmentary view partly in section taken along the line 9—9, Fig. 7.

The knitting machine indicated generally by the numeral 1 is provided with a stationary, so-called circular base 2 in which is a ring gear (not shown) for imparting rotary and reciprocatory movements to the needle cylinder 3 in slots of which are needles (not shown) said needles being moved by suitable cams to effect the knitting of fabric. At the rear portion of the circular base is fixed an upstanding and stationary bracket arm 4 to which is pivoted as at 5 a latch ring 6. Vertically movable blocks 7, 7' (Fig. 2) have attached thereto split portions 8, 8' of a cam ring upon which are mounted main and auxiliary cam assemblies 9 and 10 respectively. The cams constituting the cam assembly 9, preferably, knit the heel and toe portion of a split-foot stocking as well as the sole thereof and the cam assembly 10 controls the needles to knit the leg and instep portion. Mounted upon and upstanding from an extension of the circular base 2 is a post 11 upon the upper portion of which is fixed a stand or bracket 12 upon which are mounted several parts hereinafter to be more specifically described. The so-called

"104" gear 13 is mounted in the frame of the machine and its shaft 14 is geared to rotate four turns to one of the needle cylinder.

Mounted in the latch ring 6 above the auxiliary cam assembly 10 is a yarn lever 15 by which the leg and instep yarn 16 is fed to the needles of the knitting machine. The thread or yarn 16 passes from a source of thread supply (not shown) through thread eyelets 17 and 18 carried by arms upstanding from a bracket 19 which 10 is fastened to bracket 12 as by means of screws 20. Fastened to and upstanding from the bracket 19 and between the eyelets 17 and 18 is the thread tension mechanism 21 which removes the kinks in the thread. The said tension mechanism 21 comprises discs 22 normally retained in contact by means of a coil spring 23. From the eyelet 18 the thread 16 passes through an opening 24 (Fig. 9), under the laterally extending portion of an L-shaped rod 25 then through an opening 26. The openings 24 and 26 are provided in a tubular shaped receptacle 27 which is fastened to a plate 28 as by screws 29, the plate 28 being in turn fastened to bracket 12 as by means of screws 30. Within the receptacle or housing 27 are two parallelly disposed plates 31, 32 which together with opposite walls of receptacle 27, constitute a container for a transient dye such as 33. A pin 34 passes transversely across and is supported in opposite walls 30 of the housing 27, said pin 34 constituting a convenient means for supporting a wick 35 of absorbent material, the walls 31, 32 serving to retain the wick in position. As shown in Fig. 9 the L-shaped rod 25 is in engagement with the thread 16 momentarily retaining the same in contact with the upper surface of the wick 35 for the purpose and in a manner hereinafter to be more fully described. The L-shaped rod 25 is adjustably fastened to a laterally extending block 36 as by means of a set screw 37, a second set screw 38 serving to retain the block 36 in adjustable engagement with a downwardly extending rod 39. A collar 40 is adjustably fastened to a rod 39 as by means of a screw 41, 45 said collar serving to limit the downward movements of the rod and consequently the rod 25, said rod 39 being urged in a downward direction by means of a coil spring 42, the upper portion of which is in contact with the lower face 50 of the plate 28 and the lower portion of which is in engagement with a second collar 43 which is adjustably retained in position longitudinally of the rod 39 by means of a screw 44. Thus the spring 42 tends to maintain the rod 25 in the 55

position shown in Figs. 8 and 9 at which time the thread 16 is in contact with the wick 35 which marks the thread. To determine when the thread 16 shall be marked by the wick 35 5 in conjunction with a rod 25, the rod 39 at its lower end is pivotally connected as at 45 to a lever 46 which is pivotally connected at 47 to a bracket arm 48 fastened to the machine frame as by means of a pin 49 which is retained in 10 position in a bracket 50 depending from the machine frame as by screw 51. A screw 52 fastens the arm 48 to the pin or shaft 49. The bracket 50 is bifurcated as indicated in Fig. 1 and in the bifurcation is mounted the usual widening pick 15 bracket lever 53 which surrounds the pin or shaft 49. Between the ends of the lever 46 is fixed a depending plate 54 as by means of screws 55, the lower edge of the said plate 54 having a toe or projection 56 which is retained in contact with 20 the surface of a drum or disc 57 by the spring 42 as described. The shaft 14, upon which the disc or drum 57 is mounted, during reciprocation of the needle cylinder, rotates in the direction of the arrow so that first one notch or re- 25 cess 58 in the disc or drum 57 and then the other and diametrically opposite notch or recess 59 is brought opposite the toe 56 whereupon the spring 42 causes the rod 39 and consequently the marking rod 25 to be depressed to the positions 30 shown in Figs. 8 and 9. The provision of two notches 58, 59 permits the marking of opposite sides of the instep thread 16 during the knitting of each course of split-foot work.

The marked thread 16 after passing through 35 the opening 26 in the receptacle 27 passes through two eyelets 60 and then between jaws of a lever thread clamp 61 after which it passes through other fixed eyelets 62 and an intermediate eyelet 63 which is carried by and forms 40 part of the usual thread take-up 64. From the last eyelet 62 the thread 16 passes through an eyelet 65 (Fig. 3), through the thread or yarn lever 15 and then to the needles.

An arm 66 constituting part of the bracket 45 12 has an L-shaped bracket or plate 67 in which is swiveled a pin 68, to which is connected a depending thread indicator or scale 69. The scale 69 comprises a plate 70 more or less U-shaped in cross section fastened to which is a strip or 50 plate 71 pasted or otherwise secured to the outer face of which is a strip of paper or other material 72 which has scale markings thereon as indicated in Fig. 3. The plate 71 has secured thereto a threaded stud 73 which is engaged by 55 an internally threaded screw 74 which when turned into clamping engagement with a washer 75 retains the plate 71 in fixed position with respect to the plate 70. As shown in Fig. 6, the plate 70 has a longitudinally extending slot 76 60 through which the stud 73 passes thus permitting an adjustment of the plate or strip 71 length- wise of the plate 70.

In operation, if the stitch drawing cams 77 and 78 of the auxiliary cam assembly 10 are 65 drawing the same length of stitch the marking device shown in detail in Figs. 7, 8 and 9, periodically marks the thread 16, so that the markings on the thread such as 79, Fig. 3, will show on both sides of the instep portion equally spaced 70 from the sutures or seams connecting the instep and sole portions of the stocking. However, if either the cam 77 or the cam 78 has through excessive wear or otherwise become out of adjustment with respect to the other cam, the 75 markings on opposite sides of the stocking are

not equally spaced from the seams thereof indicating to the operator which of the said cams is drawing the longer stitch which the operator readily remedies by adjusting the cam 77 or 78 as the case may be, along the face of the cam block or cam assembly 10. Furthermore, by observing where the thread markings show with respect to the scale 72 at each reciprocation, it is possible to determine whether adjacent courses are being knitted with the same amount of 10 thread. In other words, the markings on the stocking show whether the stocking was uniformly knitted, whereas the scale indicates whether the stocking is being uniformly knitted.

Although the invention has been, for convenience, referred to in connection with a circular independent needle knitting machine adapted to knit so-called split-foot stockings, it is understood that the invention in its broader aspects, is concerned with all types of reciprocatory knitting. Other well known examples of reciprocatory knitting are: full-fashioned knitting and knitting effected on Burson, Lamb or similar types of knitting machines.

In Fig. 4 the latch ring is shown as having 25 been moved to an elevated, inoperative position, at which time an unstanding bar or rod 88 which is connected to the latch ring, engages the outer face of the thread indicator 69 moving the same to the inclined position shown. In 30 other words, to permit the latch ring 6 to be raised it is necessary to have the indicator 69 pivotally or otherwise movably mounted upon a support.

Although in the foregoing description the parts 35 and combinations thereof have been described in specific terms there has been no intention thereby to limit the invention to the precise detail of construction shown.

We claim:

1. A knitting machine having a reciprocatory needle cylinder and adapted to knit split-foot work, automatically actuated means for marking a thread during each reciprocation of the needle cylinder so that the markings on the thread 45 show the lengths of thread knitted into the fabric during successive reciprocations whereby adjustments can be readily made to effect the knitting of uniform fabric.

2. A knitting machine adapted to knit split 50 fabric and including a needle cylinder, means for automatically marking a thread during the knitting of each course of split work knitting, said means including a supply of marking fluid and a reciprocating element adapted periodically 55 to cause the thread to contact the marking fluid.

3. A knitting machine adapted to knit split- foot work including means for automatically and periodically marking a thread at least once during the knitting of each course of split work knitting, the distance between adjacent thread markings representing the length of thread knitted into the fabric during the knitting of a course of split work knitting, so that by observing the 60 positions of the markings on the thread the 65 wash-board effect in a fabric can be readily eliminated.

4. A knitting machine having two feeding stations at which two threads are adapted to be simultaneously knitted for the production of split 70 work, means for automatically marking a thread during the knitting of each course said means including a thread marking device, movable means for periodically actuating the thread marking device and connections between the 75

- thread marking device and the said movable means.
5. A knitting machine having two feeding stations at which two threads are adapted to be simultaneously knitted for the production of split work, means for automatically marking a thread during the knitting of each course said means including a thread marking device, movable means for periodically actuating the thread marking device and connections between the thread marking device and the said movable means, the said movable means including a constantly rotated element having two oppositely disposed conformations to periodically actuate the said connections and thread marking means. 10
- 15
6. A two-feed knitting machine having means for feeding at least one thread to some at least of the needles during relative movements between the needles and thread feeding means, in combination with thread marking means for automatically and periodically marking a thread in such a manner as to indicate whether or not the thread is being uniformly knitted into the fabric so that adjustments can be readily effected 20
- 25
7. A two-feed knitting machine adapted to knit split-foot work including means for automatically and periodically marking a thread at least once during the knitting of each course of split work knitting, in combination with a scale along which the thread passes, the distance between adjacent thread markings representing the length of thread knitted into the fabric during the knitting of a course of split work knitting, 30 so that by observing the positions of the markings on the thread with relation to the scale the wash-board effect in a fabric can be readily eliminated. 35
8. A thread marking device for a two-feed split-foot knitting machine including a marking wick across which a thread moves from the source of supply to the needles of the knitting machine, in combination with an automatically movable member for engaging the thread and pressing it against said wick so that the said thread shall be marked at each operation of the said movable member, the construction and operation being such that the thread markings in courses assist the operator in effecting the knitting of uniform 40
